6 Claims. (Cl. 153—1)

This invention relates to crimping devices for electrical terminals and connectors.

One known form of crimping die set for electrical connectors comprises a first crimping die having a recess therein with convergent surfaces and a second crimping die or anvil movable relatively into the recess. Upon movement of the anvil into the crimping die, the terminal is compressed and crimped onto a wire positioned in the terminal. The crimps formed by this type of die set are classified as "confined crimps" for the reason that the connector ferrule is intended to be completely circumferentially confined during at least the final stages of crimping. With this arrangement, it is apparent that since the surfaces of the recess converge towards each other, a gap will be left between the lateral edges of the anvil and the surfaces of the die during at least the initial portion of the crimping operation and in fact, it is common to design such die sets so this gap is closed only near the very end of the crimping operation.

Now, in virtually all connector crimping operations, the "flow stress" of the metal of the connector (i.e. the stress required to cause plastic deformation) is, and must be, exceeded and the metal of the connector tends to be extruded in those areas where it is not confined against extrusion. Thus, the metal of the ferrule may, and frequently does, flow axially so that the ferrule is lengthened as well as intended and/or flattened by the crimping operation. This axial flow is an expected phenomenon and is not necessarily regarded as being harmful. However, if a gap is left between the lateral edges of the anvil or second die and the surface of the recessed crimping die as explained above, the metal of the ferrule may also flow through this gap to produce extruded flanges on the ferrule after crimping. It should also be mentioned that with some connector ferrules having relatively thin walls, the ferrule wall may be sheared by the lateral edges of the anvil before it is completely confined within the recess by the crimping anvil.

Both of these results are undesirable in a confined type of crimp and are avoided if possible. According to one known method of avoiding these effects, the crimping die and anvil are made to very precise dimensional tolerances and the connector ferrule is also carefully matched dimensionally to the particular die set being used for crimping to avoid extrusion. In accordance with this method, the dies and the ferrule are formed in a manner such that the flow stress (or shear stress) of the metal of the ferrule is not imposed upon the ferrule until it has been completely circumferentially confined by closure of the gap between the crimping dies so that no undesirable radial extrusion or shearing can take place. However, if the crimping die set departs from the precise dimensional tolerances required, or if the ferrule of the connector is not carefully matched to the crimping die set, conditions exist which might give rise to the extrusion or the shearing of the ferrule as explained above.

It would thus be desirable to avoid the foregoing effects without the necessity of adhering to extremely close tolerances in the die set and the connector. Furthermore, it would be desirable to form the die set in a manner such that it could accept and crimp different sizes of ferrules without the extrusion and shearing effects described above so that a single die set might be used for different sizes of connectors.

2

It is accordingly an object of the instant invention to provide an improved die set for crimping electrical connectors. It is a further object to provide a die set having a recessed crimping die and a crimping anvil which anvil adapts itself during crimping to the dimensions of the die. It is a further object to provide a crimping anvil which is cooperable with a recessed crimping die in a manner such that during the initial stages of a crimping operation, and before the flow stress or shear stress of the ferrule is imposed upon the ferrule, the lateral edges of the anvil engage the opposed surfaces of the recess in the die to prevent extrusion or shearing of the ferrule.

These and other objects are achieved in one preferred form of the invention in which the anvil is medially slotted so that its upper portions are divided into two separate fingers. In one embodiment, these fingers are so formed that they diverge and are slightly flexible towards each other and towards the medial plane of the slot. As the anvil is moved relatively into the recess in the crimping die, the lateral edges of these fingers come into contact with the opposed convergent surfaces of the recess in the die and are cammed and flexed towards each other whereby they are maintained in close engagement with the surfaces of the crimping die. Advantageously, the crimping anvil is so dimensioned relative to the width of the recess in the die that the edges of the fingers come into contact with the sides of the recess before substantial crimping of the terminal begins so that during most of the crimping operation, the fingers are resiliently pressed against the opposed surfaces of the die recess. With this arrangement, no gap remains between the edges of the anvil and the surfaces of the die during crimping so that extrusion of the metal of the ferrule or shearing of the ferrule is prevented.

35 In the drawing:

FIGURE 1 is a frontal view of a die set in accordance with a preferred embodiment of the invention;

FIGURES 2 and 3 are views showing the crimping operation with the embodiment of FIGURE 1;

40 FIGURES 4, 5 and 6 are views similar to FIGURES 1, 2 and 3 but showing an alternative embodiment;

FIGURE 7 is a frontal view of a conventional prior art type of die set intended to perform the same type of crimping operation as the embodiments of FIGURES 1 and 4;

45 FIGURE 8 is a view showing the dies of FIGURE 7 in the closed condition at the end of a crimping operation;

FIGURE 9 is a sectional view of a crimped connection 50 formed in accordance with the prior art teachings and by a die set of the type shown in FIGURES 7 and 8 and illustrating the extrusion effects sometimes obtained; and

FIGURE 10 is a view of a crimped connection showing 55 the shearing effect which is sometimes obtained with prior art die sets.

The problem to which the instant invention is addressed can be best appreciated from FIGURES 7-10 wherein the reference numeral 2 denotes a crimping die having a recess with convergent surfaces 6 which curve towards 60 each other and merge with each other as shown at 8. The anvil block 20 has a crimping anvil 22 extending therefrom which provides an arcuate upper surface 24 adapted to receive the ferrule 10 of an electrical connector into which a conductor 12 has been inserted. Ideally, the anvil 22 should be of a width such that extrusion of the metal 65 of the ferrule 10 into the gap between the lateral edges 26 of the anvil and the surfaces 6 of the recess cannot take place. In actuality, if the recess in the crimping die is slightly oversized or the anvil is slightly undersized, or if 70 the ferrule 10 of the connector is slightly oversized, a substantial gap 23 (FIGURE 8) will remain. Upon crimping, as shown in FIGURE 8, the metal of the ferrule

will be extruded downwardly through this gap and form flanges as shown at 25, FIGURE 9. Such extrusion of the metal will take place readily with soft metal such as copper but has been observed with brass and harder connector ferrules. FIGURE 10 illustrates a condition which also arises with dies of the type shown in FIGURES 7 and 8 where a gap is left between the edges of the anvil and the opposed surfaces of the crimping die. Crimped connections as shown in FIGURE 10 are sometimes obtained if the ferrule has a relatively thin wall rather than a comparatively thick wall and the ferrule is sheared at 27 by the lateral edges of the anvil during the initial stages of crimping. The results shown in FIGURES 9 and 10 are undesirable for a number of reasons. For example, in both instances an undesirable and useless projection on the ferrule is produced which may interfere with the usage of the crimped connection in some environments where space limitations are of importance such as where the connector is of the pin and socket type and is adapted to be used in a dielectric connector block having a plurality of relatively closely spaced openings for the connectors. Furthermore, the conditions shown in FIGURES 9 and 10 result in a weakening of the connector ferrule. As previously pointed out, these conditions can be avoided by precise and accurate dimensioning of the crimping die set and careful selection of the size of the terminal being crimped. However, this solution to the problem is not always satisfactory because of the high manufacturing cost involved for precisely dimensioned dies and the inability of the tool manufacturer to control the sizes of terminals which will be crimped with the tool in use by the ultimate user.

FIGURE 1 shows one embodiment of the instant invention in which the condition shown in FIGURES 9 and 10 are avoided. In this embodiment the upper crimping die 2 is formed as is the die 2 of FIGURE 7. The lower die block 4 has an anvil 13 extending therefrom which is medially slotted as shown at 14 to form a pair of fingers 15 which in this embodiment diverge slightly from each other and from the center line of the die set. To achieve this divergence, the anvil projection 13 may be initially formed (e.g. by milling, investment casting or any other suitable method) with divergent sidewalls 17 so that after the slot 14 is cut the fingers will diverge from each other. Alternatively, the anvil projection 13 may have straight sidewalls as formed and, after the slot 14 has been cut, the two fingers 15 may be permanently deformed by being spread apart. In the disclosed embodiment the upper surfaces 16 of the fingers are of arcuate form and provide edges 18 extending along the sides of the die at the tops of the sidewalls.

In the embodiment of FIGURE 1, the width of the upper portion of the anvil projection 13 (the distance between the edges 18 of the fingers) should be such that when the anvil is moved relatively into the recess of the crimping die, these edges will come into contact with the convergent surfaces 6 prior to the imposition of any substantial compressive force on the ferrule 10 of the terminal. In use, when the crimping die and anvil move relatively towards each other and the edges 18 engage the convergent surfaces 6, the fingers 15 are cammed relatively towards each other to permit the die parts to move together. During the interval of crimping between the position of the parts shown in FIGURE 2 and the position shown in FIGURE 3, the edges 18 of the anvil are always pressed against the sidewalls so that no gap is left (as in FIGURE 8) for extrusion of the ferrule of the connector. By the same token, the danger of shearing the wall of the ferrule as shown in FIGURE 10 is avoided since the outside surface of the ferrule is supported around substantially its entire periphery.

It will be noted that some slight extrusion of the ferrule into the slot 14 of the anvil may take place during crimping as shown in FIGURE 3 and cause the formation of an axially extending rib on the external surface of the ferrule. However, it has been found that the amount of

extrusion into this slot will be limited by the fact that the tendency of each side of the ferrule to extrude into this slot counteracts the tendency of the other side to extrude and the stresses imposed upon the ferrule in this area are thus circumferentially transmitted across the top of the slot. Obviously, slot 15 should be relatively narrow in order to reduce the tendency towards extrusion since the wider this slot is made the less resistance will be offered towards extrusion.

FIGURE 4 shows an alternative embodiment of the invention in which corresponding parts with reference to the embodiment of FIGURE 1 are identified by similar reference numerals but differentiated by prime marks. In this embodiment the anvil projection 13' has straight and parallel, rather than divergent sidewalls so that when the ferrule is compressed between the surfaces 16' of the fingers and the portion 8 of the recess, the transmitted compressive forces urge the two fingers apart and against the sidewalls 6' of the crimping die. It will be apparent that the anvil 13' of the embodiment of FIGURE 4 would ordinarily be movable almost to the end of the recess in the crimping die 2 but that the fingers are spread by the terminal. This spreading of the fingers is a result of the fact that the forces transmitted through the ferrule are transmitted normally with respect to the surfaces 16' of the anvil.

It will be noted that in the embodiment of FIGURES 1-3 the wire 12 is shown as having an insulating sheath 11 thereover while in the embodiment of FIGURES 4-6 the wire is shown as being uninsulated. Both embodiments can be used with either insulated or uninsulated wires and the showing of the drawing is not intended as being limiting of the invention.

Both embodiments of the invention rely upon the principle of deforming the crimping anvil to bring the sides or edges thereof into engagement with the opposed surfaces of the crimping die thereby to confine the terminal during the crimping operation. It has been found in practice that in the case of die sets adapted to crimp relatively small terminals, the fingers of the anvil can be formed with sufficient resilience and flexibility to permit the movement as shown in FIGURES 1-6 of the drawing. It is feasible, where the die set is intended for larger size terminals, to form two parallel slots to form three fingers, the center finger being immobile during crimping while the outer fingers would deflect to adapt the anvil to the die as with the disclosed embodiments. Alternatively, it is feasible to form the anvil in two separate parts normally spring biased apart but movable relatively towards each other as in FIGURE 1 or normally biased towards each other by a separate spring but movable apart when an axial load is imposed as in FIGURE 4.

A principal advantage of the invention is that anvils and crimping dies can be manufactured, particularly in relatively small sizes, without the necessity of rigidly adhering to extremely precise, or close, dimensional tolerances and/or imposing equally precise tolerances on the terminals crimped by the tool. When the teachings of the present invention are followed, the manufacturing tolerances can be relaxed substantially and the advantages of complete peripheral confinement of the terminal will still be obtained.

Changes in construction will occur to those skilled in the art and various apparently different modifications and embodiments may be made without departing from the scope of the invention. The matter set forth in the foregoing description and accompanying drawings is offered by way of illustration only. The actual scope of the invention is intended to be defined in the following claims when viewed in their proper perspective against the prior art.

We claim:

1. A crimping die set for crimping electrical terminals onto the ends of wires comprising, a crimping die and a crimping anvil, said die having a recess with opposed

convergent surfaces for reception of an uncrimped terminal, the depth of said recess being substantially greater than the diameter of the uncrimped terminal, said anvil being adapted to enter said die recess to crimp said terminal by a confined crimp, said anvil having a relatively deep slot extending thereacross parallel to the axis thereof, said slot dividing said anvil into two fingers, said fingers being movable by flexure with respect to each other and into engagement with said convergent surfaces during crimping whereby said terminal is substantially 10 completely circumferentially confined against radial extrusion.

2. Apparatus as set forth in claim 1 wherein said fingers diverge towards their ends and the normal distance separating the lateral edges of said fingers is greater than the width of said recess at the location in said recess where a terminal is initially compressed by said die set whereby, said fingers engage said convergent surfaces and are cammed towards each other to substantially completely circumferentially confine said terminal.

3. Apparatus as set forth in claim 1 wherein said fingers are movable by flexure away from each other and away from said slot upon application of forces against their terminal engaging surfaces whereby, upon initial compression of said terminal between said crimping die and said anvil, said fingers are flexed towards, and engage, said convergent surfaces thereby to substantially completely circumferentially confine said terminal.

4. A crimping die set for crimping electrical connectors onto the ends of wires with a confined crimp comprising, a crimping die having a recess therein with opposed convergent surfaces, the depth of said recess being substantially greater than the diameter of the uncrimped terminal, a crimping anvil mounted for movement into said recess, said anvil being formed of a pair of divergent fingers, said fingers having side edges engageable with said convergent surfaces of said recess upon movement of said anvil into said recess whereby said fingers are cammed towards each other and are maintained against said convergent surfaces, and said terminal is substantially completely circumferentially confined against radial extrusion during crimping.

5. Means for crimping electrical connectors onto the ends of wires by a confined crimp comprising, a crimping die and a crimping anvil, said crimping die having a 45 recess with convergent surfaces, the depth of said recess

being substantially greater than the diameter of the uncrimped terminal, said anvil being relatively movable into said recess to compress and crimp a terminal, a relatively deep slot in said anvil extending axially thereacross, said slot dividing said anvil into two sections which are resiliently movable by flexure relatively towards and away from each other, the normal distance between the extreme lateral edges of said two sections being greater than the distance between said convergent surfaces at the location in said recess where a terminal is initially compressed between said crimping die and said anvil whereby, upon movement of said anvil into said recess, said lateral edges engage said surfaces concomitantly with initial compression of said terminal, and during further movement of said anvil, said sections are cammed relatively towards each other while being resiliently maintained in engagement with said surfaces whereby said terminal is substantially completely circumferentially confined against radial extrusion.

20 6. A crimping die set for crimping electrical connectors onto the ends of wires with a confined crimp comprising, a crimping die having a recess therein with opposed convergent surfaces, the depth of said recess being substantially greater than the diameter of the uncrimped terminal, a crimping anvil mounted for movement into said recess, said anvil being formed of a pair of fingers movable by flexure away from each other upon application of forces against their terminal engaging surfaces, the normal distance between the extreme lateral edges of said fingers being less than the distance between said convergent surfaces at the location in said recess where a terminal is initially compressed in a crimping operation between said crimping die and said anvil whereby, upon movement of said anvil into said recess, said fingers are spread apart by forces transmitted through the terminal being crimped at the outset of crimping thereby to form with said convergent surfaces a substantially complete circumferential enclosure for said terminal whereby radial extrusion of said terminal during crimping is avoided.
